UNITED STATES PATENT OFFICE.

AUGUST GARDELIS, OF PRINCETON, NEW JERSEY.

SWIMMING DEVICE.

Application filed January 14, 1921. Serial No. 437,245.

To all whom it may concern:

Be it known that I, AUGUSTUS GARDELIS, citizen of Greece, residing at Princeton, in the county of Mercer and State of New Jersey, have invented new and useful Improvements in Swimming Devices, of which the following is a specification.

This invention relates to improvements in swimming devices and has for an object the provision of a shoe which may be worn by the swimmer to increase the pressure against the water during the backward movement of the feet.

Another object is the provision of a device of this character having buoyant means for overcoming the weight of said device, so that the swimmer will not be handicapped by any additional weight.

Another object is the provision of a device of this character which includes folding wings, provision being made for limiting the movement of the wings in one direction, so as to insure their proper operation.

Other objects and advantages of the invention will appear as the following description is read in connection with the accompanying drawings.

In the drawings:—

Fig. 1 is a view showing the invention in use.

Fig. 2 is a sectional view of one of the shoes, the wings being shown in open position.

Fig. 3 is an end elevation showing the wings at the limit of their closing position.

Fig. 4 is a fragmentary view showing the wings retained in elevated position so as to permit the wearer to walk.

Referring to the drawings in detail, wherein like characters of reference denote corresponding parts, the reference character 10 indicates a shoe of any suitable or desired character. It is preferred however, to make the shoe in the form shown and to provide the same with means for securing the shoe to the ankle of the swimmer, such means being indicated at 11.

The sole of the shoe is indicated at 12 and is of a buoyant character, the purpose being to provide sufficient buoyancy to overcome the weight of the remainder of the device. For this purpose, the sole 12 is relatively

thick and hollow to provide an air compartment 13. Hingedly secured to the bottom of the sole as shown at 14, are wings 15. These wings are formed of thin light metal, such as aluminum and their inner edges are hinged to the sole 12 in transverse spaced relation so as to provide room for an extension 16. This extension is disposed longitudinally of the sole between the wings and separates the latter, the opposite walls of the said extension being formed to provide inclined stop shoulders 17, the purpose of which is to prevent the wings from contacting at the end of the forward stroke of the swimmer and to insure their positive opening during the backward stroke.

In order that the wearer of the device may walk upon the ground without removing the shoes, there is provided means for holding the wings elevated or in open position so as to raise them above the surface of the ground. This means consists in providing hooks 18 upon opposite sides of the shoe 10, for engagement with eyes 19 carried by each of the wings. As illustrated in Figure 4, the wings may thus be raised so as to space them above the surface of the ground and permit of the wearer of the shoes to walk upon the extension which separates the wings.

It is believed that when the foregoing description is read in connection with the accompanying drawings, the construction, operation and advantages of the invention will be apparent.

The right is herein reserved to make such changes in the form proportions and minor details of construction of the invention that properly fall within the scope of the appended claims.

Having described the invention what is claimed is:—

1. A swimming device comprising a shoe, a relatively thick hollow sole included in the shoe, a hollow extension disposed centrally and longitudinally along the bottom of and communicating with the interior of the sole, said hollow extension co-operating with the sole to provide a buoyant shoe, oppositely disposed downwardly and outwardly inclined walls provided on the extension and wings hingedly secured along

one of their edges at the juncture of the shoe and extension.

2. A swimming device comprising a shoe, wings having their inner edges hingedly secured to the sole of the shoe, an extension carried by the sole and located between the wings to limit their movement toward one

another, eyes carried by the wings and hooks secured to the sides of the shoe and removably engaging said eyes to hold the ¹⁰ wings against movement.

In testimony whereof I affix my signature.

AUGUST GARDELIS
